EGG GRADER

Elmer J. Gross, Chicago, Ill.

Application August 9, 1952, Serial No. 303,550

15 Claims. (Cl. 209—121)

This invention relates to devices for automatically grading eggs according to weight.

The main objects of this invention are to provide an improved candling and grading device requiring a minimum of attention by an operator; to provide a device of this kind in which the candling and grading are done in one handling operation, the candler merely placing the selected eggs in a trough from which they are automatically withdrawn in succession and discharged into separate compartments of a receiving tray; to provide improved dispensing mechanism for automatically delivering the eggs, one at a time, from an inclined chute; to provide improved transfer mechanism for lowering the eggs from one runway to another; to provide improved mechanism for timing the operation of such transfer mechanism; to provide improved interconnection between the transfer mechanism and the automatic dispensing mechanism so that the delivery of eggs occurs in harmonious relation to the reciprocating movements of the transfer mechanism; and to provide an improved form of grading runway of segmental form in which a series of weighing scales controls the passage of eggs of different weight to different delivery chutes.

Other objects will appear from the following description and drawings which are directed to a specific illustrative embodiment of the invention, and in which:

Figure 1 is a perspective front view of an egg candling and grading machine constructed according to this invention, the front wall of the casing being shown hinged at the bottom and turned down to expose the internal mechanism to view.

Fig. 2 is a fragmentary perspective view of the transfer mechanism by means of which the eggs are lowered from the receiving runway and delivered in timed sequence to the grading runway.

Fig. 3 is a fragmentary perspective view of a portion of the egg grading runway on a somewhat larger scale than Figure 1 and showing the co-acting relation of the weighing segments to the dumping segments of such runway.

Fig. 4 is a detail of the same in similar projection showing the latch mechanism in its normal position for preventing tilting of a dumping segment.

Fig. 5 is a detail of parts of the same viewed from the left of Fig. 4.

Fig. 6 is a perspective view corresponding to Fig. 4 showing how the latch mechanism is actuated under the weight of an egg sufficient to depress the weighing segment.

Fig. 7 is a similar view showing the position of the latching elements during the tilting of the dumping segment.

Fig. 8 is a perspective view of the automatic trip mechanism that controls the delivery of eggs from the receiving runway to the transfer bucket.

Fig. 9 is a detail in perspective of a detent member for controlling the passage of eggs from the receiving runway.

Figs. 10, 11, 12, 13 and 14 are details in side elevation, partly in section, showing successive steps in the interaction of the devices that control the delivery of eggs to the transfer bucket.

5 In the form shown in the drawings, the egg grader comprises a receiving magazine in the form of a trough-like runway 1 which is slightly inclined toward its delivery end and shaped so that eggs will roll freely thereon, a bucket 2 that carries the eggs downward and discharges them on an egg grading runway 3 that is divided into a series of aligned grading units comprising weighing segments 4 alternating with dumping segments 5 and corresponding in number of units to the number of weight grades into which the batch of eggs is to be divided.

As shown, the receiving runway 1 is inclined downward toward the right of Figure 1 and the delivery runway 3 is inclined downwardly toward the left of Figure 1 so that the eggs to be graded will roll from right to left by their own gravity. Along the rear side of the grading runway there is a platform 6 that inclines down rearwardly and that has mounted thereon, adjacent to each one of the dumping segments 5, a pair of tracks 7 with guard rails 8 of slightly higher elevation than the tracks 7 for proper delivery of eggs from the dumping segments.

20 Behind the platform 6 there is a tray, not shown which will be understood to be divided by partitions running from front to rear for separation of the delivered eggs of different grades. Tubular clips 9 on the platform 6 are provided for receiving dowel-like projections on the 25 front ends of the subdividing partitions of the delivery tray.

The supporting frame of the machine is partly enclosed by a housing 10, of which the front wall 11 extends throughout the length of the machine and is hinged 30 along its bottom edge so that it may be swung from the open position in which it is shown in Figure 1 to a closed position in which the wall 11 will be upright and the inclined shelf 12 will slope downward toward the grading runway 3 with its edge 13 located at approximately the 35 level of the runway 3. The shelf 12 and a similar shelf 12.1 on the rear wall of the housing prevent any possibility of the eggs falling off of runway 3 when dumped from the bucket 2.

The extension 14 of the front wall 11 has a turn-button 40 15 positioned to engage a matching aperture 16 for holding the wall 11 in its upright position.

A candling lamp 17 is mounted at the front side of the supporting frame and the front wall 11 has a lamp housing 18 with a lens tube 19 against which the operator holds the eggs for candling inspection before they are placed upon the runway 1.

The receiving runway 1 has downwardly converging guard flanges 20 to assure the proper centering and rolling of the eggs along the tracks 21 of this runway. The delivery end of this runway is more sharply inclined, as shown in Figs. 1 and 8, utilizing a part of the weight of the eggs to operate the automatically shiftable detents that control the delivery of eggs from this runway. In the form shown there are three detents that are interrelated, the first and second control the approach of eggs in single file order to delivery position where the third detent holds the foremost egg on the delivery chute until the transfer bucket comes to a position to receive it.

The structure and operation of these detent mechanisms will best be understood from Figs. 8 to 14 inclusive. A channel-shaped frame 22 is mounted below the tracks 21 and has pivoted thereon, by means of a shaft 23, an L-shaped cradle structure 24 having an upright abutment forming a first detent 25 at its receiving end and having a pair of horizontally disposed parallel tracks with rounded shoulders forming a second detent

26 near its delivery end. The detent 25 has a latch lever 27 pivotally mounted on its front face on a horizontal pin 28. When the detent 25 is elevated as in Fig. 9, the latch lever 27 is normally urged by gravity to a position in which its upper arm 29 stands somewhat in front of the detent 25, and its lower arm 30 seats on a cross-bar 31 of the frame 22.

The trip latch lever 27 normally falls by gravity toward the position with respect to the detent 25 in which it is shown in Fig. 9; that is, with the cheek flanges of the lower arm 30 resting against the lower part of the detent 25 so that when the cradle 24 is in the position in which it is shown in Figs. 9 and 11, the lower end of the trip lever 27 will rest on the crossbar 31 and lock the member 24 against tilting.

When the first egg A of Fig. 10 comes in contact with the trip lever 27, it shifts the lower arm 30 to the left of the crossbar 31 and allows the cradle 24 to tilt by gravity to the position shown in Fig. 10. Further rolling of the egg A will depress the detent shoulders 26, restoring the latch lever 27 to the locking position in which it is shown in Fig. 9, allowing the egg A to roll toward the right as in Fig. 11.

Immediately beyond the right hand end of the cradle 24, there is a third detent arm 32 of a bell crank lever pivoted at 33 on the frame 22, which lever has an arm 34 that rests on a frame bar 35. This arm 34 extends under the adjacent end of the cradle member 24 and prevents the detent 32 from being tilted when the cradle is locked as in Fig. 11. An egg A is therefore held on the runway by detent arm 32 until after a second egg B trips the latch 27 as indicated in Fig. 12. Detent 25 now stops egg B until egg A is released by detent 32.

Tripping of the detent 32 is controlled by a bell crank lever 36 which is pivoted on the frame 22 and has a blade-like arm 37 that will be swung into the position shown in Fig. 11 where it locks the detent arm 32 in egg-stopping position, if the bucket 2 is not in position to receive an egg.

If, however, the bucket 2 is in its egg-receiving position, the arm 37 occupies the position in which it is shown in Fig. 12. Now inasmuch as the egg B has tripped the latch 27, the detent 32 swings down allowing the egg A to roll into the bucket 2. The corresponding movement of the arm 34 and the pull of gravity causes the cradle 24 to rock into the position in which it is shown in Fig. 13, allowing the egg B to roll into contact with the shoulders 26 as shown in Fig. 13, where it is held until the cradle 24 is released by the arm 34. The bell crank lever 36 has an arm 38 which determines the position of the arm 37 through movement of a guide member 39 on bucket 2 and the detent arm 32 has a lug 40 which stops the movement of the arm 37 in the position shown in Fig. 14; but the arm 37 has an aperture 41 into which the lug 40 may pass when the parts are in the position shown in Fig. 13.

The weight of the egg A now causes the bucket 2 to descend, depressing the bell crank arm 38 and raising the arm 37 as shown in Fig. 14. This lifts the detent arm 32 to its egg-stopping position and retracts the arm 34, whereupon the weight of the egg B rocks the cradle 24 to the latched position in which it is shown in Fig. 11 and allows that egg to roll to the position A in that figure. This sequence of operations is repeated for each egg that rolls down the runway 1.

The elevator bucket 2 is elevated and lowered by gravity under control of the mechanism, shown in detail in Fig. 2, which comprises a post 41 that is raised and lowered while being maintained in a vertical position by parallel motion levers 42 and 43 pivoted at 44 and 45 on a frame member 46. The lever 43 has an arm 43.1 that carries an adjustable weight 47 that slightly overbalances the weight of the bucket 2 and its supporting connections, so that the bucket 2 is normally urged by gravity to the egg-receiving position in which it is shown by full lines

in Figs. 8 and 2, in which position the arm 43.1 rests on a limit stop 48.

The bucket 2 is fixed on an arm 49 pivoted at 50 on post 41 and connected by a link 51 with lever 43, whereby 5 the arm 49 is tilted by the lever 43 so that in its lowered position 49.1, the bucket 2 will be tilted to the dumping position 2.1 for delivering an egg to the grading runway 3.

The weight 47 is adjusted along the arm 43.1 to a point where the smallest egg that is delivered to the 10 bucket 2 will overbalance the counterweight and cause the bucket to descend until it is stopped by coming into contact with the track of grading runway 3.

A weighted pawl 53, pivoted at 54 on the arm 43 at a point between the bucket and the pivot 45, has a nose 15 55 that engages teeth on the ratchetwheel 56 to control the speed of descent of the bucket 2. The ratchetwheel is driven at constant speed in the direction of the arrow 57 by an electric motor 58 and thus times and controls the descent of the bucket, causing the egg to be delivered 20 without shock to the runway 3. As soon as the egg leaves the bucket 2, the counterweight 47 elevates the bucket 2 and the pawl 53 rides idly back to its initial position, as shown in full lines in Fig. 2.

The guide member 39 is a loop of wire fixed on the 25 bucket 2 in position to raise the bell crank lever arm 38 and lower the arm 37 so as to release the egg-retarding detent 32. When the bucket 2 is in its elevated position for receiving an egg at the position A in Fig. 11, the 30 detent 32 will still be locked by cradle 24, bearing on the arm 34 unless and until the latch 27 has been released by the next egg B as shown in Fig. 12, whereupon the egg B 35 tilts the cradle and rolls against the shoulders 26, while egg A rolls into the bucket 2, tilting the detent 32 and raising its bell crank arm 34 to hold the cradle 24 in the position where its shoulder 26 blocks the movement of egg B, as shown in Fig. 13. The descent of the bucket 2 under the weight of egg A allows bell crank arm 38 to fall raising arm 37 to lock detent 32 in its egg holding position. Cradle 24 is now free to yield under egg B, 40 as indicated in Fig. 14, and returns to its latched position while egg B rolls into contact with detent 32. The cradle 24 has a counterweight 59 to help tilt the cradle 24 to the position shown in Fig. 10.

The grading runway 3 comprises a series of segments 45 certain of which (designated by the numeral 4) are part of the mechanism for selecting the eggs according to weight, and others of which (designated by the numeral 5) are parts of dumping mechanisms for discharging the eggs according to weight from the runway 3.

50 Each section of the runway 3 comprises a plate 60 bent to trough-form with upstanding flanges straddled by longitudinally split rods of rubber which serve as tracks 61 along which the eggs roll. Each segment 4 is tiltable longitudinally on a transverse horizontal pivot 62 mounted on a stationary frame 63 and has a depending leg 64 that rests on one arm of a medially fulcrumed balance beam 65, the other arm of which carries an adjustable weight 66. In the form shown, the beam 65 extends through a block 67 which is fulcrumed at 68 so as to be sensitive to the weight of an egg on the runway segment 4. Tilting of the segment 4 under the weight of an egg is limited by a stop 69 which may be a plate stuck out from the floor aof the frame 63.

55 Each dumping segment 5 of the runway 3 is mounted on a longitudinally disposed pivot 70 carried by brackets 71 on the stationary frame 63 so that the segment 5 may tilt rearwardly on its pivotal axis to discharge an egg that has rolled onto it from the preceding weighing segment 4. An arm 72 extends forward from the segment 5 and carries a counterweight 73 which normally restores the segment to its position of horizontal track alinement with the adjacent segments 4.

60 Pivoted at 74 on the bracket 71 is a latch member 75 which rests by gravity on the balance beam 65 and 70 has a detent shoulder 76 that abuts against a lip 77 on

a latch member 78 that is pivotally mounted at 79 on a crossbar 80 of the track segment 5. The latch member 78 has a shoulder 81 that engages a lug 82 on the crossbar 80 to limit the movement of the latch member 78 on its pivot 79, so that it is normally urged by gravity to the position in which it is shown in Fig. 4. When the track segment 4 is depressed by the appropriately predetermined weight of an egg rolling on it, the scale beam 65 is tilted into contact with the stop 69 (as shown in Fig. 6), the latch member 75 will fall with the beam 65 to a position which will allow the lip 77 to pass clear of the shoulder 76 when the track section 5 is tilted by the egg.

The latch member 75 is bifurcated at its free end to provide a recess 83 into which the lip 77 can pass to permit the tilting of the track segment 5 as indicated in Figs. 6 and 7. The lower edge of the latch member 75 has a shoulder 84 that engages a shoulder 85 on the scale beam 65 and thus locks the segment 4 in its depressed position, as shown in Fig. 6, for a short time while the egg passes from the segment 4 onto the segment 5 which is now free to tilt, since lip 77 of the latch member 78 enters the recess 83 in the latch member 75.

As the dumping segment 5 tilts, the lip 77 passes into the recess 83, engages the bottom edge of the finger 86 of the latch member 75 and thus lifts the shoulder 84 from the shoulder 85 on the scale beam and allowing the segment 4 to return to its normal position. Upward tilting of the latch member 75 is limited by the stop 87, and tilting of the track segment 5 is limited by the shoulder 88 on latch member 78 coming into contact with the end of the finger 86 on the latch member 75 as shown in Fig. 7.

As soon as the egg has left the dumping segment 5, weight 73 returns segment 5 to its runway alignment with segment 4 and the latch members 78 and 75 fall by gravity to the position shown in Fig. 4. Any egg of insufficient weight to tilt the first segment 4, of course, fails to unlatch the respective segment 5. Successive segments 4 are set for lesser weights of eggs according to desired grading.

In order to assure the proper deflection of an egg through the tilting of the dumping segment 5, this segment 5 is provided with a frog rail 89 which normally lies out of the way between the tracks 61, so that the eggs that are not to be deflected will roll freely along the rails 61.

In the form shown, the frog member is made of a piece of wire of somewhat twisted U-shape, with its frog portion 89 disposed diagonally between the tracks 61, with one arm 90 extending through a hole 91 in plate 60, being bent so as to offer no resistance to the tilting of the segment 5 and terminating as a pivot in an aperture 92 in the adjacent frame bracket 71, and with the other arm 93 extending through a hole in plate 60 and pivoted in the bar 80 of the dumping segment 5. The pivot of arm 93 is close to the track 61 that is nearest the pivot 70 about which the dumping segment tilts. Thus the frog portion 89 occupies a retracted position between the tracks in the normal position of the segment but tilts with the segment 5 and projects upward when the segment 5 is tilted to discharge an egg. As dumping segment 5 tilts, the arm 90, running through the perforation 91 in the plate 60, cams the curved frog rail 89 into position to cause the rolling egg to turn and roll freely onto the tracks 7 leading to the receptacle for the respective grade of eggs.

The operator, after candling an egg at the lens 19, lays the egg on the receiving runway 1 which serves as a magazine from which eggs are withdrawn automatically. The leading egg will roll by gravity along said runway until it strikes the trigger 27 on the detent 25, causing the lower arm 30 of the trigger to swing to the left clear of the stop bar 31. This allows the cradle 24 to tilt to withdraw detent 25, as shown in Fig. 10, allowing the egg A to pass on as indicated. The egg on striking shoulders 26 tilts the cradle 24 and allows the egg A to

roll against the detent 32. As the egg travels over the shoulder 26 on the cradle 24, the trigger member 27 is returned to its locking engagement with the bar 31 and cradle 24 bearing on bell crank arm 34 prevents tilting of detent 32 until the trigger 27 is tripped by a succeeding egg B, as indicated in Fig. 12. If the elevator bucket 2 is in position to receive the egg A, the detent 32 will yield and allow the egg A to roll into the position A.1 while the trigger 27 is held released. In the meantime egg B rolls to the position on cradle 24 where it is shown in Fig. 13. The passage of the egg A over the detent 32 lifts the arm 34 so as to block the tilting of the cradle 24 and to stop egg B.

The weight of the egg in the bucket 2 causes the bucket 15 2 to fall and its speed of descent is limited by the engagement of the nose 55 of pawl 53 against the teeth of the ratchetwheel 56. As the bucket descends, the guide 39 swings the bell crank arm 38 downward, causing the bell crank arm 37 to restore and lock the detent 32 to its upright position, as shown in Fig. 14. This retracts arm 34 and allows cradle 24 to yield to let egg B roll into contact with detent 32 and to return the cradle to its latched position.

As the bucket 2 approaches the upper limit of its 25 movement, the guide 39 raises the bell crank arm 38. This swings the arm 37 downward releasing the detent 32 to allow the egg to roll into the bucket, when a succeeding egg tilts the approach cradle 24 to release the bell crank arm 34.

30 The eggs, having been lowered one at a time and delivered to the grading runway, roll along that. Only an egg of the heaviest grade will depress the first weighing segment 4 and free the adjacent segment 5 so as to be discharged into the respective chute 7, each succeeding 35 weighing segment 4, having been adjusted to the weight of its particular grade of egg, will trip the latch levers to operate the respective dumping segments.

Through the timing action of the ratchet 56 and pawl 55, the eggs are delivered rapidly but are spaced at 40 correct intervals to allow the weighing and dumping mechanisms to perform their functions and return to normal position before a succeeding egg arrives. The motor driven wheel 56 and pawl 53 make up a preferred form of timing mechanism which controls the rate of descent of the bucket under the weight of an egg. Except for 45 the use of this motor-driven timing mechanism, all mechanical movements in the apparatus are automatically actuated and controlled by the weight of the eggs as they roll along the tracks and are conveyed by the bucket.

50 Although but one specific embodiment of this invention is herein shown and described, it will be understood that numerous details of the construction shown may be altered or omitted without departing from the spirit of the invention as defined by the following claims.

55 I claim:

1. In an egg grader, a frame, a downwardly inclined runway thereon shaped to roll eggs by gravity to its delivery end and comprising an egg weighing segment and a dumping segment, said weighing segment being movable vertically from normal to depressed positions under a predetermined weight of an egg rolling along said runway, said dumping segment being normally urged to its runway position and being tiltable sideways out of such position through the weight of an egg thereon, latch 60 means between said weighing segment and said dumping segment comprising a first latch member pivoted on said frame and normally urged to engage and move with said weighing segment, and a second latch member on said dumping segment, said first latch member being positioned to abut said second latch member to prevent tilting of said dumping segment when said weighing segment is in its normal position and to shift away from such abutment when said weighing segment is depressed from its normal position.

70 2. In an egg grader, a frame, a downwardly inclined

runway thereon shaped to roll eggs by gravity to its delivery end and comprising an egg weighing segment and a dumping segment, said weighing segment being movable vertically from normal to depressed positions under a predetermined weight of an egg rolling along said runway, said dumping segment being normally urged to its runway position and being tilttable sideways out of such position through the weight of an egg thereon, latch means between said weighing segment and said dumping segment comprising a first latch member pivoted on said frame and normally urged to engage and move with said weighing segment, and a second latch member on said dumping segment, said first latch member being positioned to abut said second latch member to prevent tilting of said dumping segment when said weighing segment is in its normal position and to shift out of such abutment when said weighing segment is depressed from its normal position, said first latch member being adapted to hold said weighing segment in a depressed position and said second latch member being adapted to release said first latch member from holding relation to said weighing segment through the tilting movement of said dumping segment.

3. In an egg grader, a downwardly inclined runway shaped to roll eggs by gravity to its delivery end and divided into a series of egg weighing segments alternating with dumping segments, said weighing segments being movable vertically under successively decreasing weights of eggs rolling along said runway, each said segment comprising a pair of spaced parallel rails, each said dumping segments having a laterally curved frog rail between its rails shiftable with said dumping segment for deflecting an egg to one side from its path along said runway, said frog rail being normally retracted from such path, an arm pivoted on said frame at one side of the pivotal axis of said dumping segment and attached to said frog rail and adapted to project said frog rail upward relatively above the runway rails to deflect an egg to one side, and latch means normally holding each said dumping segment stationary and being releasable through movement of the respective weighing segment.

4. In an egg grader, a frame, a downwardly inclined runway shaped to roll eggs by gravity to its delivery end and comprising a weighing segment and a dumping segment, a counterweighted balance beam supporting said weighing segment, said dumping segment being tilttable laterally between egg receiving and dumping positions and normally urged into its egg-receiving position of substantial alignment with said weighing segment, latch means mechanically controlling the tilting of said dumping segment, said latch means comprising coacting members, one pivoted on said frame and engaging said balance beam to move therewith and the other mounted on said dumping member, said latch members being positioned and shaped to engage each other to lock said dumping segment against tilting when said weighing segment is in normal alignment therewith and to pass out of such engagement when said balance beam is tilted by a predetermined weight of an egg on weighing segment.

5. In an egg grader, a frame, a downwardly inclined runway shaped to roll eggs by gravity to its delivery end and comprising a weighing segment and a dumping segment, a counterweighted balance beam supporting said weighing segment, said dumping segment being tilttable laterally and normally urged into substantial alignment with said weighing segment, latch means mechanically controlling the tilting of said dumping segment, said latch means comprising a pair of coacting members, one pivoted on said frame and movable with said balance beam and the other mounted on said dumping member, said latch members being positioned and shaped to engage each other to lock said dumping segment against tilting when said weighing segment is in normal alignment therewith and to pass out of such position for locking engagement when said balance beam is tilted by a predetermined weight of an egg on weighing segment, coacting shoul-

ders on said one latch member and said balance beam to lock said beam in a tilted position, and shoulder means on said one latch member positioned to be engaged by said other latch member to release said beam through the tilting movement of said dumping segment.

6. In an egg grader, an inclined runway comprising a weighing segment tilttable longitudinally of the runway, a dumping segment normally aligned with said weighing segment and tilttable laterally for discharging eggs from the runway, a balance beam controlling the movement of said weighing segment, latch means controlled by said balance beam for locking said dumping segment against tilting, a receiving magazine for eggs located above said runway and comprising a chute shaped and disposed to deliver eggs by gravity in single file succession, a bucket movable vertically by the weight of an egg from an elevated position for receiving the egg from said chute to a depressed position for delivering such egg to said runway, a balanced supporting means for said bucket normally urging same upward to its egg receiving position, and timing means controlling the descent of said bucket.

7. In an egg grader, an inclined runway comprising a weighing segment tilttable longitudinally of the runway, a dumping segment normally aligned with said weighing segment and tilttable laterally for discharging eggs from the runway, a balance beam controlling the movement of said weighing segment, latch means controlled by said balance beam for locking said dumping segment against tilting, a receiving magazine for eggs located above said runway and comprising a chute shaped and disposed to deliver eggs by gravity in single file succession, a bucket movable vertically by the weight of an egg from an elevated position for receiving the egg from said chute to a depressed position for delivering such egg to said runway, supporting means for said bucket comprising a balance beam normally urging said bucket upward to its egg receiving position, and timing mechanism comprising a ratchet wheel driven at constant speed and a pawl pivoted on said balance beam and bearing on said ratchet wheel to control the descent of said bucket.

8. In an egg grader, an inclined runway comprising a weighing segment tilttable longitudinally of the runway, a dumping segment normally aligned with said weighing segment and tilttable laterally for discharging eggs from the runway, a balance beam controlling the movement of said weighing segment, latch means controlled by said balance beam for locking said dumping segment against tilting, a receiving magazine for eggs located above said runway and comprising a chute shaped and disposed to deliver eggs by gravity in single file succession, a bucket movable by the weight of an egg from a position for receiving the egg from said chute to a position for delivering such egg to said runway, supporting means for said bucket comprising a frame member, a balance beam pivoted on said frame, a vertically disposed stem pivotally connected to said bucket and to one arm of said balance beam, a counterweight on the other arm of said balance beam, a link pivoted to said frame and to said stem in parallel motion relation to said balance beam, and timing mechanism comprising a ratchet wheel driven at constant speed and a pawl pivotally carried by said supporting means and coacting with said ratchet wheel to control the descent of said bucket.

9. An egg grader, comprising a grading runway, a receiving magazine for eggs located above said runway and comprising a chute shaped and disposed to deliver eggs by gravity in single file succession, a bucket movable by the weight of an egg from a position for receiving the egg from said chute to a position for delivering such egg to said runway, a balanced supporting means for said bucket normally urging same to its egg receiving position, detent means at said chute comprising a first detent member pivoted on an axis transverse to the chute having detent shoulders at its ends in bell crank relation so as to be alternately effective to block the passage of an egg and

retractable by the weight of an egg at each such detent shoulder, a second detent member pivoted on an axis transverse to said chute and having a detent arm effective to block the passage of an egg and being normally retractable under the weight of an egg in contact therewith, said second detent member having a bellcrank arm positioned to block the tilting of said first detent member through the retraction of said detent arm, and latch means movable through the movement of said bucket to lock said second detent member in egg blocking position when said bucket is lowered.

10. The combination of claim 9 in which said latch means is normally urged into position to lock said second detent and is retracted from such locking position through the movement of the bucket to its egg-receiving position at said chute.

11. In an egg grader, a grading runway, an inclined receiving runway above said grading runway, a bucket movable up and down between said runways for transfer of eggs from said receiving runway to said grading runway, an approach detent member pivoted on a transverse axis below said receiving runway and having first and second detent shoulders at opposite sides of said axis and positioned for alternate movement into and out of the path of an egg along the runway through the tilting of said detent member, a delivery detent member pivoted on a transverse axis below said receiving runway beyond said approach detent member, said delivery detent member having a detent arm movable into and out of the path of an egg along said runway and having a bell crank arm extending under the adjacent end of said approach detent member, and a latch acting between said approach detent member and said runway and normally urged to hold said approach detent member in the position where it coacts with said bell crank arm to lock said delivery detent member's detent arm in the path of an egg when said approach detent member is latched.

12. In an egg grader, a supply runway inclined downward and shaped to roll eggs in single file to its delivery end, a delivery detent at said end pivoted on a transverse axis to tilt into and out of egg-holding position and having a rearwardly directed bell crank arm, an approach detent member pivoted on a transverse axis and having first and second detent formations at opposite sides of its pivotal axis adapted alternately to stop the advance of an egg toward said delivery end and to be retracted through tilting of said approach detent member, said bell crank arm being shaped and positioned to coact with said approach detent member to hold said delivery detent in its egg-holding position when said approach detent member is tilted to retract second detent formation and to tilt said approach detent member backward to shift said second detent formation to its egg-holding position when said delivery detent is tilted out of its egg-holding position, and latch means on said approach detent member adjacent said first detent formation being normally urged to prevent backward tilting of said approach detent member and adapted to be released through contact with an egg approaching said first detent formation.

13. In an egg grader, a supply runway inclined downward and shaped to roll eggs in single file to its delivery end, a delivery detent at said end pivoted on a transverse axis to tilt into and out of egg-holding position and having a rearwardly directed bell crank arm, an approach detent member pivoted on a transverse axis and having first and second detent formations at opposite sides of its pivotal axis adapted alternately to stop the advance of an egg toward said delivery end and to be retracted through tilting of said approach detent member, said bell crank arm being shaped and positioned to coact with said ap-

proach detent member to hold said delivery detent in its egg-holding position when said approach detent member is tilted to retract the second detent formation and to tilt said approach detent member backward to shift said second detent formation to its egg-holding position when said delivery detent is tilted out of its egg-holding position, latch means on said approach detent member adjacent said first detent formation, being normally urged to prevent backward tilting of said approach detent member and adapted to be released through contact with an egg approaching said first detent formation, a transfer bucket movable toward and away from an egg-receiving position at said delivery runway end, and a bell crank having one arm controlled by the movement of said bucket and having another arm coacting with said delivery detent to lock the latter in its egg-holding position and release the same only when said bucket is at its egg-receiving position.

14. In an egg grader, a supply runway inclined downward to roll eggs in succession toward its delivery end, a series of three detents along said runway for stopping eggs rolling on said runway, the first and second of said detents being connected to each other to form a member rockable about an intermediate transverse axis for alternate movement of the detents into and out of the path of an egg on said runway, the third said detent being rockable about a transverse axis into and out of said path and having a bell crank arm coacting with said member to hold each one of said second and third detents in its egg-stopping position when the other is out of such position, latch means normally acting for holding said member in the position where the second detent is out of the egg-stopping position, said latch means being held inactive through contact with an egg on said runway, and each said detent being movable out of the path of eggs by the weight of an egg thereon.

15. In an egg grader, a supply runway inclined downward to roll eggs in succession toward its delivery end, a series of three detents along said runway for stopping eggs rolling on said runway, the first and second of said detents being connected to each other to form a member rockable about an intermediate transverse axis for alternate movement of the detents into and out of the path of an egg on said runway, the third said detent being rockable about a transverse axis into and out of said path and having a bell crank arm coacting with said member to hold each one of said second and third detents in its egg-stopping position when the other is out of such position, latch means normally acting for holding said member in the position where the second detent is out of the egg-stopping position, said latch means being held inactive through contact with an egg on said runway, and each said detent being movable out of the path of eggs by the weight of an egg thereon, a transfer bucket movable toward and away from an egg-receiving position at said delivery runway end, and a bell crank having one arm controlled by the movement of said bucket and having another arm coacting with said third detent to lock the latter in its egg-holding position and release the same only when said bucket is at its egg-receiving position.
